UNITED STATES PATENT OFFICE.

CHARLES F. KENWORTHY, OF WATERBURY, CONNECTICUT.

ANNEALING-FURNACE.

1,169,494.

Specification of Letters Patent. Patented Jan. 25, 1916.

Application filed September 28, 1914. Serial No. 863,811.

To all whom it may concern:

Be it known that I, CHARLES F. KENWORTHY, a citizen of the United States, residing at Waterbury, in the county of New Haven and State of Connecticut, have invented certain new and useful Improvements in Annealing-Furnaces, of which the following is a specification, reference being had therein to the accompanying drawings.

10 My invention relates to a new and improved annealing furnace, and has for its object, among other things, to provide a furnace within which to anneal non-ferrous metals bright or free from oxidation; to so 15 arrange the parts that the furnace may be easily and quickly loaded and unloaded; and to provide mechanism whereby the pyrometer thermo-couple may be placed so that the exact temperature of the annealing chamber, and the metals therein, may 20 be accurately determined.

To these and other ends, my invention consists in the annealing furnace, having certain details of construction and combinations of parts, as will be hereinafter described and more particularly pointed out in the claims.

Referring to the drawings, in which like numerals of reference designate like parts 30 in the several figures: Figure 1 is a sectional side elevation of one form of my improved invention, taken upon line C—D of Fig. 2; Fig. 2 is a sectional plan view thereof, taken upon line A—B of Fig. 1; 35 Fig. 3 is an enlarged sectional view of the exhaust and suction valve mechanism; Fig. 4 is an enlarged plan view of the elevator mechanism; and Fig. 5 is a fragmentary elevation thereof.

40 My improved furnace may be fired either with coal, coke, oil, or any other means, or by fuel from a gas producer which may be located adjacent to the annealing furnace or at a distant point, whichever may seem 45 the most desirable under the circumstances, and the arrangement of the parts, as shown in the accompanying drawings, and set forth in the following description, are only 50 for the purpose of illustrating the general form of my invention, and its method of application.

In the drawings, the numeral 1 designates 55 one form of a gas producer, and 2 the furnace or retort, in which is an annealing chamber 3 that is entirely surrounded by a chamber 4, within which the products of

combustion circulate, the same being admitted thereto through the port 5 connected with the gas producer. Concentric with the chamber 3 is a similar chamber 6, which is 60 connected with the port 5 at the throat 7, and with the open air through the port 8.

As the products of combustion from the gas producer pass through the port 5, the air in the chamber 6 that is admitted 65 through the port 8 is heated and passes through the throat 7 and mingles with the products of combustion in the port 5, and then circulates within the chamber 4, heating the annealing chamber and escaping 70 into the open air through the port 9.

The furnace or retort 2 is fixed to the platform 10, which in turn is supported upon the upper end of the sealing tank 11, into which projects the flange 12, preferably 75 integral with the platform 10 and flaring outwardly from the bottom of the annealing chamber 3 into the liquid within said sealing tank 11, the normal top surface of which is indicated by the broken line 13. 80

Surrounding the plate 10, and also supported upon the top of the sealing tank 11, is the grate bar platform 14, upon which the operator stands, and providing a convenient place for the work both before and 85 after the annealing operation. Fixed against rotation in the foot block 15 at the bottom of the sealing tank, and the head block 16, connected with the top of the furnace, is a piston rod 17, having an opening 90 18 through the end thereof, which connects the port 19 that opens through one side of said piston.

The elevator platform consists essentially 95 of a lower cylinder head 20, an upper cylinder head 21, between which is the cylinder 22, and each having the usual packing glands 23, connected therewith, a piston head 24, fixed to the piston rod 17 by the pin 25, platform arms 26 connected 100 with the lower cylinder head 20, joined at their outer ends by the tie bar 27, and each carrying a platform 28, near their outer ends. Each of these platform arms 26 is additionally secured to the cylinder 22 by 105 the brace bars 29 and clamp 30.

On the platform 28 are secured the hollow uprights 31, so as to lie substantially parallel with the cylinder 22. These provide retaining means to hold the work in 110 place on the platforms 28. They may be utilized also for supporting a plurality of

shelves 32, separated by the collars 33, if the character of the work is such that it can be better handled in this manner. The number of these parallel shelves may be varied as may be desired.

Upon the underside of each of the platforms 28 are the bars 34 connected with the arms 26, and to which are fixed the stop arms 35, which engage stop blocks 36 fixed 10 to the inside of the sealing tank 11 to limit the movement of the platforms about the piston rod 17. When either of the stop arms are in engagement with either of the stop blocks, one of the platforms is in register with the annealing chamber 3, and the other platform with one of the openings 37, through the platform 14. Attached to the lower cylinder head 20 is a bracket 38 carrying a friction roll 39 that contacts with a 20 plate 40 fixed within the sealing tank 11 or other convenient place, whenever either one of the platforms are in register with the annealing chamber 3.

While one of the platforms 28 is being 25 loaded, the other platform is within the annealing chamber, the general position of the parts at this time being substantially as shown in Fig. 1.

The parts connected with the platform 28 30 project up through either one of the openings 37 in the grate bar platform 14, and after the annealing process is completed, the platform is lowered to the position substantially shown by broken lines in Fig. 1, at 35 which time both the platforms 28 are within the liquid in the tank 11, and are moved about the axis of the piston so as to bring the platform last taken from the annealing furnace into register with one of the openings 36, at which time the last loaded platform is brought into register with the annealing chamber, the stop arms 35 by their contact with the stop blocks 36 limiting these movements. The platforms are now 40 elevated, during which time the friction roll 39 by its contact with the guide plate 40 (see Fig. 4) prevents the rotation of said platforms, and the platform having the new work thereon is moved into the annealing 45 chamber, and the other platform is elevated above the grate bar platform 14 through one of the openings 37, and is then unloaded and reloaded.

The guide plates 40 do not extend to the 50 bottom of the tank 11 (Fig. 1), so that when the platforms 28 are in their down position the roll 39 is below the bottom of said plates and can be moved about the axis of the piston with the platform. When, however, 55 either one of the platforms is in line with the annealing chamber, the roll 39 is in line with either one of the guide plates 40 and contacts therewith as soon as the platforms have moved upwardly a limited distance.

60 The platforms are elevated by forcing wa-

ter through the opening 18 and port 19 into the cylinder 22, the pressure of which is exerted against the upper cylinder head 21 and the platform raised. To lower the platform, the pressure upon the water in the 70 opening 18 is released and the weight of the platform forces the water in the opposite direction through the port 19 and opening 18 by the contact of the head 21 with said water.

75 A pyrometer thermo-couple, designated by the numeral 41, is placed within one of the hollow uprights 31 on each of the platforms 28 and moves therewith into and out of the annealing chamber. The upright 80 within which the pyrometer thermo-couple is inserted is connected with a pipe 42 by the pipes 43. The pipe 42 is of such length as to project above the top of the grate bar platform 14 when the platforms are in their 85 down position. Through the pipes 42 and 43 pass flexible lead wires (not shown), from the pyrometer located outside of the furnace to the thermo-couple connected with each of the platforms 28. By reason of this 90 arrangement of the thermo-couple the actual temperature of the metal within the annealing chamber is determined and the flexible leads are kept dry and out of the liquid within the sealing tank 11. It has been 95 found in practice that this method of mounting the thermo-couple adds materially to the life thereof and very much materially reduces the cost of the annealing process.

100 As the annealing chamber is entirely free from the products of combustion, bright metals are annealed free from fire or oxidation and do not require subsequent polishing or cleaning, as is the practice in the annealing furnaces now in common use.

105 Fixed to the furnace 2 over the annealing chamber 3, is a combined suction and exhaust valve, which consists essentially of a body portion 44 having oppositely disposed radiating members 45 and 46 connected 110 therewith, to the open ends of which are threadably secured the valve bushings 47, each of which is provided with a valve 48, valve stems 49, springs 50, collar 51 and nuts 52. It will be observed, however, that the 115 valves 48 operate at opposite ends of the valve bushings 47, the one connected with the radiating member 45 being upon the outside of the valve bushings 47 and the valve 48 connected with the radiating member 46 120 upon the inside of the valve bushings 47.

125 If, when the loaded platform is being raised to the annealing chamber, it should be very wet, or, due to the shape of the work thereon, carries liquid with it, the liquid evaporates very quickly within the annealing chamber and passes off through the lifting of the valve 48 connected with the radiating members 45.

130 When lowering the platform, after an

annealing operation, into the tank 11, steam is very apt to form, and if formed passes off through the same valve. Sometimes, however, a vacuum is formed within the annealing chamber, which, if not broken, will cause the liquid within the tank 11 to be drawn up into the annealing chamber, and thus cause injury thereto. This is prevented, however, by the valve 48 connected with the 10 radiating member 46, which is pulled off its seat by the vacuum, which is thereby released.

Fixed to the body portion 44 is a mirror frame 53, within which is a pane of glass 55 and a mirror or reflector 54. The latter is not essential, however, and may be arranged in a different position or angle if desired. The object of this reflector and pane of glass is to provide means for observing the 20 interior of the annealing chamber and the conditions as presented therein through the opening 56 in the mirror frame 53.

There are minor changes and alterations that can be made within my invention, aside 25 from those herein suggested, and I would therefore have it understood, that I do not limit myself to the exact construction herein shown and described, but claim all that falls fairly within the spirit and scope of my 30 invention.

Having described my invention, what I claim as new and desire to secure by Letters Patent, is:

1. In a device of the character described, 35 the combination with an annealing chamber; means for heating the same without admitting the products of combustion thereto; means for automatically freeing said chamber from steam or liquid comprising a valve 40 held on its seat by means that will withstand a predetermined pressure; and means for breaking a vacuum if formed therein comprising a valve similar to the one above referred to, but operating in the opposite 45 direction.

2. In a device of the character described, the combination with an annealing chamber; of a liquid tank beneath said annealing chamber; means for loading and unloading 50 said annealing chamber, said means comprising a plurality of platforms; means for operating said platforms, whereby the same may be moved in a line substantially parallel

with said annealing chamber and in a path at substantially a right angle thereto, a portion of said means being upon the outside 55 of said annealing chamber and substantially parallel therewith.

3. In a device of the character described, the combination with an annealing chamber; of a liquid tank beneath said annealing chamber; means for loading and unloading 60 said annealing chamber, said means comprising a movable cylinder, a fixed piston, a piston head on said piston and within said 65 cylinder, a plurality of platforms connected with said cylinder at one end; means for limiting the rotary movement of said platforms about said piston; and means for preventing the rotation of said platforms about 70 said piston when the same are being moved in a direction substantially parallel therewith.

4. In a device of the character described, the combination with an annealing chamber; of a liquid tank beneath said annealing chamber; means for loading and unloading 75 said annealing chamber, said means comprising a plurality of platforms having a fixed relation to each other; means for operating 80 said platforms, whereby the same may be moved as a unit in a line substantially parallel with said annealing chamber, and in a path at substantially a right angle thereto; and means for securing a pyrometer thermo- 85 couple to each of said platforms and protecting the leads thereto from contact with the liquid in said tank during the movement of said platforms.

5. In a device of the character described, 90 the combination with an annealing chamber; of a liquid tank beneath said annealing chamber; means for loading and unloading said annealing chamber, said means comprising a platform; means for operating the 95 same; a pyrometer thermo-couple and means for securing the same to said platform and protecting the leads thereto from contact with the liquid in said tank during the movement of said platform.

In testimony whereof I affix my signature in presence of two witnesses.

CHARLES F. KENWORTHY.
